UNITED STATES PATENT OFFICE.

WISDOM MCGILL, OF WACO, TEXAS.

LOCK.

Specification of Letters Patent.

Patented Oct. 4, 1921.

1,392,514.

Application filed February 15, 1921. Serial No. 445,090.

To all whom it may concern:

Be it known that I, WISDOM MCGILL, a citizen of the United States, residing at Waco, in the county of McLennan and State 5 of Texas, have invented certain new and useful Improvements in Locks, of which the following is a specification.

This invention relates to improvements in locks and has for its principal object the provision of a lock which on account of its 10 novel and unique construction and operation is unusually strong in its locked position, and is also so arranged in its mechanism as to require prior knowledge thereof before 15 operation, such arrangement therefore tending to make the lock more secure against its unauthorized manipulation.

Other advantages will become apparent as the description of the invention progresses, 20 reference being had to the accompanying drawings forming part hereof in which—

Figure 1 is a vertical sectional view of the lock in position on a door and illustrating the mechanism of the lock and showing the 25 bolt in its fullest extended position in the door jamb.

Fig. 2 is a similar view illustrating one side of the lock with its plate partly broken away, the bolt in locked position and showing the vertical rack bar for further securing 30 the bolt.

Fig. 3 is a cross-sectional view taken on line 3—3 of Fig. 1.

Fig. 4 is a front or face view of the rack 35 bar, and

Fig. 5 is a side view of the key for the lock.

Referring more particularly to the drawings, 1 denotes a section of a door which is 40 mortised to receive the body 2 of the lock. The door frame 3 is also mortised for a bolt receiving member 4 for the bolt 5 which member 4 is extended upward and has a slot 45 for slidably receiving a vertical rack bar 6 operated by a pin 7 and pinion 8, the rack bar having an eye 9 to allow the bolt 5 to pass therethrough. The bolt 5 is provided with teeth 10 in mesh with a small pinion 11 carried on a pin 12 by means of which 50 the bolt 5 may be moved in and out of the body 2 by a button 13.

A vertical bolt 14 under tension of a spring 15 co-acts with a small horizontal bolt 17 also under spring tension 18. Fig. 2 55 shows the bolt 5 in locked position without using the rack bar 6.

When desired to lock the main bolt 5 in the door jamb as shown in Fig. 1, the lugs 19—19 of the key are inserted in the key hole 20 and the lugs will press upon the 60 spring 15 on rotation of the key to pull down the bolt 14 out of engagement with the notch 16, thereby causing the bolt 17 to pass into the notch 17^a in the bolt 14. The button is then rotated to bring the lock bolt 5 outward 65 in the position shown by dotted lines in Fig. 1. The vertical rack bar 6 is now passed downward to allow the end of the bolt 5 to pass through the eye 9 and the bolt continued inward until the notch 16 in the end 70 of the bolt registers with the bolt 14 and slides into the notch. The end 18^a of the key is now inserted in the slot 19^a, and the bolt 17 pushed aside, causing the bolt 14 to pass into the notch 16. The lock can if 75 desired be used without the rack bar 6.

The lock bolt 5 may also be used as a latch and as shown in Fig. 1 is provided with a spring 21 which bears against the end of the bolt 5, the forward end of the 80 latch bolt 5 being beveled as at 5^a. The lock may also be used on the outside of the door without the need of mortising if desired and a suitable latch member affixed to the door facing.

Having thus described the nature and objects of my invention, what I claim as new and desire to secure by Letters Patent is—

1. A lock of the character described, comprising a bolt with a substantially U-shaped 90 formation on one end and a notch in the formation, the shank of the bolt provided with teeth meshing with a pinion rotated by a pin to move the bolt outward and inward in the body of the lock, a vertically disposed 95 bolt under spring tension for locking the U-shaped bolt in locking position, a horizontally arranged bolt for securing the vertical bolt out of engagement with the U-shaped bolt, and auxiliary means for securing the 100 U-shaped bolt in locked position.

2. A lock of the character described, comprising a bolt with a substantially U-shaped formation on one end and a notch in the formation, the shank of the bolt provided 105 with teeth meshing with a pinion rotated by a pin to move the bolt outward and inward in the body of the lock, a vertically disposed bolt under spring tension for locking the U-shaped bolt in locking position, a horizontally arranged bolt for securing the vertical bolt out of engagement with said U-shaped 110

- bolt, and a rack bar with an eye, said bar disposed in the door jamb for receiving and securing the U-shaped bolt in locked position.
- 5 3. A lock of the character described, having a U-shaped locking bolt with teeth on its shank and co-acting with a pinion rotated by a pin for moving the bolt in and out of the body of the lock, a vertically arranged 10 bolt for securing the U-shaped bolt in locked position, a horizontally disposed bolt for holding the vertical bolt out of engagement
- with the U-shaped bolt, a spring adjacent one end of the U-shaped bolt and so arranged that the bolt may be used as a latch and auxiliary means for securing the U-shaped bolt in locking position.

In testimony whereof I have signed my name to this specification.

WISDOM ^{his} ~~McGILL~~ _{mark}
